UNITED STATES PATENT OFFICE.

JAMES H. PETERS, OF NECHESVILLE, TEXAS.

CLOTH-MEASURING REEL.

SPECIFICATION forming part of Letters Patent No. 251,936, dated January 3, 1882.

Application filed August 19, 1881. (No model.)

To all whom it may concern:

Be it known that I, JAMES H. PETERS, of Nechesville, in the county of Anderson and State of Texas, have invented a new and Improved Cloth-Measuring Reel; and I do hereby declare that the following is a full, clear, and exact description of the same, reference being had to the accompanying drawings, forming part of this specification, in which—

10 Figure 1 is a front elevation. Fig. 2 is a vertical section through the line $x x$ of Fig. 1, looking in the direction of the arrow, and showing a roll of cloth in position. Fig. 3 is a rear elevation. Fig. 4 is an enlarged detail view of the registering devices.

My invention relates to certain improvements in cloth-measuring reels, designed principally for measuring bagging, carpets, &c.

This class of inventions consists usually of 20 a supporting-frame, a roller upon which the cloth is wound off the roll, and a cutting-board and measuring-roller, against which latter the cloth bears in its travels, and the revolutions of which roller are made to register and indicate by audible signals the number of yards payed off.

My invention consists in the peculiar combination and arrangement of the cutting-board with two standards, whereby the said cutting-board is made to act as a sufficient brace for the frame, as well as to perform the offices of a cutting-board.

The invention also consists in means for producing a variable tension on the cloth as it 35 passes from the roll to the reel, whereby the tendency of different thicknesses of cloth to wind the cloth in greater or less lengths than the register indicates is compensated for and corrected.

40 The invention also further consists in the peculiar construction and arrangement of the various parts of the device, whereby a very much cheaper, simpler, and more effective reel is produced, as will be hereinafter more fully described.

In the drawings, A represents the base-frame, which is made of four pieces jointed in rectangular shape. From the ends of this base-frame there rise two rigid vertical standards, 50 B B. In notched bearings in the lower part of these standards is placed the roll-shaft C,

upon which is placed the roll of cloth, bagging, or carpet which is to be measured and cut. Upon this shaft are two detachable wooden heads, a a, which rest at the ends of the roll 55 of material. In open bearings in the top of the standards B B is journaled the reel-shaft D, which is made square and provided with a crank-handle for turning it, and also with pointed hooks, upon which the edge of the cloth is 60 fastened to permit it to be wound upon the reel.

About midway between the roll-shaft and reel-shaft is fixed the cutting-board E, which is arranged in a more or less vertical plane between the standard, and has tenons on its ends, 65 that enter mortises in the standards. Near the cutting-board are two rods, F F', one of which, F, is on one side of the board, near the top, and acts as a tie-rod, while the other one, F', is on the other side of the cutting-board 70 and near the bottom. This rod F' acts both as a tie-rod to hold the cutting-board firmly to the standards and as a tension or guide rod, over which the cloth is directed before it is passed to the measuring-roller. (See Fig. 2.) 75

G is the measuring-roller, which is located upon the opposite side of the cutting-board from the tension rod F' and near the bottom of said board. This roller has a plain periphery with teeth or points on the same, which, 80 by engagement with the cloth, prevent the latter from slipping and give a positive movement to the roller exactly equal to the feed of the cloth. Upon the end of the journal of this roller is arranged a short crank or tappet arm, 85 b, Fig. 4, which is made to act upon registering-wheel H to record the number of revolutions of the roller. The periphery of this roller being made to equal a certain portion of a yard— 90 as a quarter, for instance—every four revolutions constitute one yard. The wheel H is accordingly laid off for twenty-five yards into one hundred subdivisions, for which there are one hundred peripheral teeth, into which the short crank or tappet of the measuring-roller successively engages, and by which latter the said 95 wheel is moved one tooth for each revolution of the roller.

To lock the registering-wheel against any displacement that might occur between the revolutions of the tappet-arm b, I place between the registering-wheel H and the nearest 100

standard a vertically-sliding detent, I. This consists of a plate which has two slots, *c c*, in it, through which screws pass to guide it and loosely connect it with the standard, and which detent is cut away with a half-round cut where it approaches the journal of the registering-wheel, and is re-enforced by a stiffening-rib, *d*. This detent is arranged in vertical position and extends from the lower edge of the wheel to a point above the same, where it has a tooth, *e*, that drops into the notches of the wheel, and also a handle, *f*, that allows said tooth to be lifted out at will. This detent I cause to be operated by the tappet-arm *b*, which latter lifts against the lower edge of the detent, removing the tooth *e* from the notches just before it acts upon the wheel to turn it. Then just as the tappet leaves the wheel-notch the detent falls down of its own gravity and locks the wheel again.

In arranging the cutting-board in the standards its tenons are made shorter than the mortises in which they are seated, so that the cutting-board has an adjustment up and down, which adjustment may be fixed at any desired point by set-screws or other devices.

Referring to Fig. 2, it will be seen that the cloth passes from the roll at the bottom over the tension-rod *F'*, thence under the cutting-board, thence around the roller which does the measuring, and thence to the reel above. Now, I have found that it is impossible to measure different thicknesses of cloth, carpet, or bagging around the same roller unless the tension is regulated according to the thickness of the cloth. This is so by reason of the fact that the middle line of the cloth is the line of measurement, while the outer surface is the surface that gives motion to the roller. Now, with very thin material this difference is so slight as to involve little or no difference; but with a very thick material a greater quantity of material is reeled off than is actually registered, and to counteract this variation I adjust the cutting-board downwardly with a greater tension for the heavier stuffs, so as to stretch them sufficiently over the roller to compensate for the variation. This I consider to be a feature of great merit. Another great advantage of my invention is the making of the cutting-board also to fulfill the function of a brace, whereby the construction of the carrying-frame

is very greatly simplified and cheapened, there being only three elements in said structure—the base, the standards, and the cutting-board. 55

In making use of my invention I shall use such proportions in the size of the machine and its parts as the nature of the work to be done requires.

To produce an audible signal for every yard 60 measured, a series of twenty-five pins are arranged upon the inner side of the registering-wheel, and are made to bear against a snap-spring to give such signal.

I am aware of the fact that an adjustable 65 stretching-board has been placed between the stock-roll shaft and the reel-shaft of a cloth-stretcher, and I therefore do not claim this feature of an adjustable board, except when combined with a measuring-roller and located 70 to bear on the cloth between the stock-roll and the said measuring-roller, it being obvious that the varying of the tension for my purpose only has value in connection with the measuring devices that indicate the aliquot parts of the 75 cloth.

Having thus described my invention, what I claim as new is—

1. The combination of a base-frame having two vertical standards, B B, a stock-roll, C, 80 located in bearings in the bottom of the said standards, a reel-shaft, D, located in bearings in the top of said standards, the combined cutting-board and brace E, arranged in the standards between the roll C and reel D, and the 85 measuring-roller G' and tension-rod F', located upon opposite sides of the said cutting-board, as described.

2. In a cloth-measuring machine, the combination, with the measuring-roller, its registering devices, and the stock-roller, of an adjustable cutting-board located to bear upon the cloth between the measuring-roll and stock-roll, as and for the purpose described. 90

3. The combination of the measuring-roller, 95 having tappet *b*, the toothed registering-wheel, and the detent I, adapted to be operated by the same tappet *b* that actuates the wheel, substantially as and for the purpose described.

JAMES H. PETERS.
